A. H. FRANKE.

OIL FILTER,

APPLICATION FILED APR. 24, 1920.

1,402,411.

Patented Jan. 3, 1922.

TO INVENTOR
AUGUST H. FRANKE
BY Edward E. Langdon
ATTY.

UNITED STATES PATENT OFFICE.

AUGUST H. FRANKE, OF ST. LOUIS, MISSOURI.

OIL FILTER.

1,402,411.

Specification of Letters Patent.

Patented Jan. 3, 1922.

Application filed April 24, 1920. Serial No. 376,234.

To all whom it may concern:

Be it known that I, AUGUST H. FRANKE, a citizen of the United States of America, and a resident of the city of St. Louis, and State 5 of Missouri, have invented certain new and useful Improvements in Oil Filters, of which the following is a specification containing a full, clear, and exact description, reference being had to the accompanying drawings, 10 forming a part thereof.

My invention relates to improvements in oil filters, and has for its primary object a filter which has two precipitating chambers and a series of baffle plates in each precipitating chamber to aid in the precipitation of foreign particles in the oil.

A further object is to construct an oil filter having precipitating chambers in which the circulation of the oil is induced by heat 20 applied around the precipitating chamber and the direction of circulation controlled by baffle plates.

In the drawings,
25 Fig. 1 is a cross sectional view of my filter;

Fig. 2 is a top plan view, taken on the line 2—2 of Fig. 1.

In carrying out my invention, I make use of a reservoir 9, which is divided into compartments 10 and 11. The reservoir 9 is surrounded on four sides and the bottom by a steam jacket 12, to which a steam pipe 13 is connected. Near the bottom of the steam jacket is a pipe connection 14, which is secured to a riser 15. This pipe in turn is connected to a second pipe 16 by means of a short pipe 17 and the valves 18 and 19. These valves regulate the amount of condensation allowed to remain in the steam chest or 40 jacket.

In the chamber 10 is placed a rectangular casing 20, which is provided with a plurality of baffles 21. These baffles are provided with a central opening 22, around which is a 45 depending flange 23. This flange extends almost entirely around the opening 22 but is cut away adjacent the passage 23 so that oil striking the bottom of the baffle plate can pass out through this opening after circulating around the flange 22. The chambers 50 10 and 11 are separated from each other by the partition 24, which has a recess 25 cut in its upper end so that oil may pass from the compartment 10 into the compartment 11. 55 In the compartment 11 is located a second rectangular casing 26, which is spaced apart

from the wall or partition 24 so as to form a passageway 27. This will cause the oil passing from the chamber 10 to the chamber 11 to enter the last mentioned chamber near 60 its bottom, and flow upward through and past the baffles 28.

Above the baffles 28 is a flange 29, having an upturned edge 30, this flange and upturned edge extending entirely around the 65 compartment 26, and over the upturned edge is placed a pan 31 having the opening 32 which will permit the oil to pass therethrough and come in contact with the folded plate 33. This plate is folded so as to make 70 a plurality of V-shaped passages through which the oil is circulated, and over the plate 33 is placed a second pan 34, which supports a similar folded plate 35; the folds of this plate extending at rightangles to the folds in 75 plate 33, having the V-shaped passages extending at rightangles to the passages in the plate 33. At a short distance above the plate 35 is a second flange 36, which supports a pan 37 having in its bottom an opening 38, 80 and on this pan is supported a folded plate 39 similar to the plates 33 and 35.

This folded plate in turn supports still another pan 40, and in turn another folded plate 41 is placed thereon, the folds in plate 85 41 extending at rightangles to the folds in the plate 39, said plate having its folds extending at rightangles to the folds in plate 39. Entering the chamber 11 and above the last mentioned folded plate is a pipe 42, 90 which is connected to the filtering chamber 43. This filtering chamber is provided with a downwardly extending wall 44 so as to form a passageway 45 which directs the oil downward toward the bottom of the chamber 43.

Within the chamber 10 is placed a receiving box 59 which is provided with an opening 60, which connects with the pipe 61 and delivers oil into the bottom of the chamber 10. Within the receiving box 59 is a flange 62, on which the straining bag 63 rests. This straining bag is provided with a wire frame 64 on its upper end, its lower end being provided with a loop 65. Within the 105 bag is placed a spreader 66, this spreader being wider at the bottom than at the top, and is provided on two of its sides with the recesses 67. In order to secure the spreader 66 within the bag 63, the end having the loop 65 is pulled upward through the central opening 68 and a wire passed through the 110

loop. This wire will rest in the recesses 67 and prevent the end of the bag from dropping downward.

As will be seen in Fig. 1, the baffles in the 5 chamber 10 are provided with openings 69, the purpose of these openings being to allow moisture to settle in the bottom of the chamber 10. The chambers 10 and 11, as well as the filtering chamber 43, are provided with 10 drain cocks 70, these being for the purpose of cleaning the chambers and drawing off liquids therefrom.

The arrows shown in the refining chambers indicate the direction of the induced 15 currents set up by the heating of the oil. These induced currents assist in the depositing of foreign matter.

The operation of my invention is as follows:

20 The oil is first poured into the receiving chamber 59 and passes through the strainer 63. This will remove the large particles of foreign matter contained in the oil. The oil then passes downward through the pipe 61 25 into the chamber 10 where the moisture is precipitated, as well as some of the particles of foreign matter which have passed through the strainer. As this compartment fills, the oil will overflow the successive baffles until 30 the cut-out portion 25 in the wall 24 is reached. The oil will then pass down between the wall 24 and the frame 26 to the bottom of the chamber 11 and then rise again over the successive baffles and graduated plates till it reaches the level of the pipe 35 42. After flowing through the pipe 42 the oil passes down the passageway 45 formed in the filtering chamber and thence upwardly until it comes in contact with the filtering 40 bags. It will then flow through the walls of these filtering bags and through the connection into the oil reservoir 51 where the pure oil is located. During its travel in the chambers 10 and 11 additional or induced currents 45 are set up, due to the peculiar arrangement of the baffles and to the heating walls, the portion of the oil in contact with the wall adjacent the steam chamber becoming hotter than the oil removed therefrom, and consequently rising. This will cause the oil to 50 eddy around in the various chambers, even though no additional oil is being supplied to the filter.

The filtering bags located in the chamber 55 43 are merely for straining out suspended particles which have passed through the straining cloth 63, and which are too light to be precipitated by gravity.

Having fully described my invention, what I claim is—

1. An oil filter comprising adjacent refining compartments, a heating jacket surrounding said compartments on three sides, a passageway between said compartments, said passageway opening near the top of one compartment and near the bottom of the adjacent compartment, an oil strainer located in the top of one of these compartments, a pipe extending therefrom and terminating near the bottom of the compartment, a plurality of truncated pyramid-shaped baffles located in said compartment and around said pipe and spaced apart therefrom, a plurality of truncated pyramid-shaped baffles located in the remaining compartment, a plurality of folded plates located above said baffles, means for draining oil from the top of the last mentioned compartment and means for supplying heat to the heating jacket.

2. An oil filter comprising a refining compartment, a heating jacket surrounding said compartment on three sides, a plurality of truncated pyramid-shaped baffles located in said compartment, said baffles being open at their center so as to provide an uninterrupted vertical passageway, an oil strainer mounted above said compartment, a pipe attached to said strainer and opening downward through the openings formed in the baffles and terminating near the bottom of said compartment, a second compartment located adjacent the first compartment, said second compartment being surrounded on three sides by the heating jacket, a passageway connecting said compartments, said passageway opening near the top of the first mentioned compartment and terminating near the bottom of the second mentioned compartment, a plurality of truncated pyramid-shaped baffles located in said second compartment, said baffles being open so as to form an uninterrupted vertical passageway through said compartment, a plurality of folded baffles located above the first mentioned baffles, said last mentioned baffles having their folds so arranged as to form passageways extending at right angles to each other, plates for separating said folded baffles, a pipe attached near the top of the second mentioned compartment for draining oil therefrom and means for supplying heat to the heating jacket.

In testimony whereof, I have signed my name to this specification.

AUGUST H. FRANKE.
